UNITED STATES PATENT OFFICE

2,151,023

SAUCER FOR SUPPORTING CUPS, GLASSES, OR OTHER DRINKING VESSELS

Alan Carruthers Gibson, London, England

Application February 14, 1938, Serial No. 190,484
In Great Britain March 6, 1937

1 Claim. (Cl. 65—15)

The present invention relates to a saucer for supporting a cup, glass or other drinking vessel, the saucer being of the kind in which a cup or the like is supported out of contact with liquid lodging in the saucer.

According to this invention, the saucer is formed with two liquid-receiving portions, one being in the form of a central well and the other in the form of a surrounding gutter. These two portions are separated from one another by a ledge on which the cup rests out of contact with spilled liquid which may have collected in either of these two portions.

The cup-supporting ledge is surrounded by a ridge which serves to centre the cup and assists in preventing a spoon from slipping into the well.

One form of construction of the invention is illustrated in the annexed drawing, in which:

Fig. 1 is a sectional elevation of a cup in position on a saucer.

Fig. 2 is a plan of the saucer, and

Fig. 3 is a sectional elevation of a stack of saucers.

In the drawing, *a* represents a cup of ordinary shape and *b* represents a saucer in accordance

with this invention. This saucer is formed with a central well *c* above which the cup *a* is supported, and also with a second liquid-receiving portion in the form of an annular gutter *d* of which the outer edge extends to the periphery 5 of the saucer. The liquid-receiving portions *c* and *d* are separated from one another by a ledge *e* upon which the cup rests. A ridge *f* surrounds the ledge *e*, and serves to centre the cup and assists in preventing a spoon from slipping into the 10 well *c*.

Having thus described the nature of the said invention and the best means I know of carrying the same into practical effect, I claim:

A saucer of the kind in which a cup or the like 15 is supported out of contact with liquid lodging in the saucer, characterised in that the saucer is provided with two liquid-receiving portions, one being in the form of a central well and the other in the form of an annular gutter, the two portions being 20 separated from one another by a ridge from which extends a ledge on which the bottom of the cup rests, and such ledge extending inwardly towards the central well.
